REGISTERING RENEWABLE PLUG FUSE

Filed May 11, 1927

UNITED STATES PATENT OFFICE.

JAMES P. GILLIAM, OF LOS ANGELES, CALIFORNIA, ASSIGNOR OF ONE-HALF TO HENRY W. BERKMEYER, OF GLENDALE, CALIFORNIA.

REGISTERING RENEWABLE PLUG FUSE.

Application filed May 11, 1927. Serial No. 190,503.

My invention is a registering renewable plug fuse of the type having a screw threaded plug by which it may be secured in a socket, and including a fuse to break the electrical circuit of which it forms a part in the event of overload or short circuit.

An object of my invention is the construction of a registering renewable plug fuse preferably of the screw type, in which when the fuse is broken an indication is given by the movement of one of the plug elements showing that such fuse has been burned.

In constructing my invention I utilize a tubular insulating body with a screw threaded jacket thereon to form one terminal. Inside of the body I have a contacting spring engaging with the conducting jacket. A core is slidable in the main insulating body and is constructed of insulating material. This has a conducting element thereon to engage the contact spring and on the end of the core is a second terminal. The fuse in the form of a loop or a bar with perforations is secured to the end terminal and to the conducting element on the core. This holds a slidable part of the core in retracted position against the action of the compression spring and, on releasing of the fuse, part of the core is thrust outwardly.

My invention is illustrated in the accompanying drawings, in which:

Figure 1 is a longitudinal sectional view of the fuse plug, the plane of section being taken on the line 1—1 of Fig. 2.

Figure 2 is a transverse sectional view taken on the line 2—2 of Fig. 1 in the direction of the arrows.

Figure 3 is a sectional view similar to Fig. 1 with the movable end of the core thrust outwardly.

Figure 4 is an inner end view of the plug, the direction of view being indicated by the arrow 4 of Figure 3.

Figure 5 is a longitudinal sectional view taken on the line 5—5 of Fig. 1 in the direction of the arrows.

Figure 6 is a side view of the plug, taken in the direction of the arrow 6 of Fig. 1, with the conducting jacket removed.

Figure 7 is an outer end view of the plug, taken in the direction of the arrow 7 of Fig. 5.

Figure 8 is a side view of the core, taken in the direction of the arrow 8 of Fig. 9.

Figure 9 is a view of the core, taken in the direction of the arrow 9 of Fig. 8.

Figure 10 is a view of the core, taken in the direction of the arrow 10 of Fig. 9.

Figure 11 is a detail perspective view of the contact spring.

Figure 12 is a view of the core, similar to Fig. 8, with the fuse ring removed and the head thrust outwardly.

The outside body of the plug comprises a tubular shell 11 which has a head 12 at one end, a cylindrical part 13 adjacent thereto, a screw threaded section 14, and a small end 15. This shell has a hexagonal internal bore 16. A slot 17 is cut through one side of the shell, preferably at the screw threaded part, and part of these threads are cut away at an adjacent part 18. The shell is provided with longitudinal grooves 19 in the walls of the bore 16. A conducting jacket 20 is threaded on the screw threads and underneath this jacket is a conducting spring 21. This spring has a flat portion 22 with a flange 23, the flange fitting over the end 24 of the screw threads 14. The spring 21 also has a section 25 bent inwardly and a reverse bend 26, there being a flat contacting part 27 with a longitudinal slot 28 therethrough, the piece terminating with an inwardly bent flange 29, the slot extending partly into said flange. (See Fig. 11.) This contacting spring is held in position by being jammed by the jacket 20 against that portion 18 of the shell from which the threads have been cut away.

The core, designated generally by the numeral 30, has a stationary or base part 31 which is hexagonal on the outside and has longitudinal ribs 32 sliding in the grooves 19. The base 31 has a head 33 fitting in a seat 34 against a shoulder in the end of the shell. A deep recess 35 is formed in the base, extending from the end 36, and there are a pair of slots 37 and 38 which extend through the wall of the base into this recess. A conducting strip 39 is secured on the end of the base by means of a screw 40, this screw forming a contact adapted to seat upon the spring contact of the conventional socket. A prong 41 extends outwardly from the conducting strip 39. The base is preferably made of an insulating material.

The indicating head 42 of the core has an end or head piece 43, preferably formed of insulating material, which is screw threaded on a tubular bar 44, there being a shoulder 45 to limit the threading of the head. A conducting plate 46 is secured to this tubular

plug by means of a bolt 47 and this plate slides in the slots 37 and 38 in the base of the core. One end of the plate extends through the slot 38 and has a prong 48 thereon, and 5 the fuse 49 is positioned upon the prongs 41 and 48 with the prongs engaged within the apertures 50 in each end of the fuse 49. A spring 51, under compression between the base of the recess and the conducting plate 10 46, urges the indicating head and the tubular bar 44 outwardly, this motion of the bar 44 and head 42 being normally prevented by the fuse 49.

The manner of operation and functioning 15 of my plug is substantially as follows:

When the various elements of the plug are assembled and the fuse fitted over the prongs 41 and 48, it will be seen that this fuse holds the base part and the movable head section of 20 the core together, with the spring 51 compressed. The plate 46, after being fitted in the shell, presses the end of the fuse on the prong 48 against the portion 27 of the conducting spring 21, the prong sliding in the 25 slot 28. Therefore, the plug when inserted in the socket forms an electric connection through the jacket 20, the spring 21, the conducting plate 46, the fuse 49, the prong 41, the conducting plate or strip 39 and the screw 30 40, the head of the screw 40 and the jacket 20 forming the contacts in the socket.

If the fuse burns, the resistance restraining the spring 51 is removed and the spring thrusts the movable head of the core outwardly from the position shown in Fig. 1 to 35 that shown in Fig. 3. Therefore, a person inspecting the plug may readily ascertain by noting the head end 43 thrust outwardly that the fuse has been burned in this plug. It will 40 thus be seen that in installations in which a large number of fuse plugs are required, that a quick inspection will show which particular plug or plugs are fused. Such plugs may 45 then be unscrewed from the socket, the core may then be readily withdrawn, and a new fuse bar placed on the prongs 41 and 48, the core being then reinserted in the shell and the whole plug again connected in the socket.

A portion of the conducting plate 46 adjacent the prong 48 has a flat end 52 and the end 53 of the conducting strip 39 adjacent the prong 41 is also flat, as shown in Fig. 12. These flat surfaces give sufficient area for the 50 transmission of current through the fuse link 55 which is connected onto the prongs. One end of the link is pressed against the end 52 by the spring 21.

The tubular bar 44 may be utilized as a receptacle for spare fuse links or bars, as 60 when the core is removed the head 43 may be unscrewed from this tubular bar. It is to be noted, however, that when the plug is assembled that the head 43 cannot be unscrewed even when thrust outwardly into the position shown in Fig. 3, and it will be necessary 65

for a person to remove the whole plug from a socket and thus throw a certain number of lights out of circuit in order to remove fuse links.

Various changes may be made in the principles of my invention without departing from the spirit thereof, as set forth in the description, drawings and claims.

I claim:

1. A fuse plug having a tubular shell with 75 a contact element thereon, a core fitting in the shell having a stationary base with a contact element thereon, a slideable head in the core, means normally thrusting said head outwardly, a conducting structure between the 80 contact element on the shell and the head, a fuse bar connected between the head and the contact end of the base holding said head in retracted position.

2. A fuse plug comprising in combination 85 a tubular shell having an electrical contact thereon, a core having a stationary base with a second contact, the core having a slideable head with a conducting element, a conducting means between the contact and the shell 90 and the said conducting element, a fuse bar, means to connect said fuse bar between the conducting element on the head and the contact on the base, and means to thrust the head outwardly on the fusing of said bar.

3. A fuse plug having a tubular shell with a screw threaded conducting jacket thereon, a core having a base fitting in said shell, the base having a contacting and a conducting element thereon, a head slidably mounted in 100 the core having a conducting plate, a fuse bar connected between the conducting plate and the conducting element on the base, a conducting spring between the jacket and the said conducting plate, and a compression 105 spring in the core thrusting the head outwardly on fusing of the fuse bar.

4. A fuse plug having a tubular shell with a conducting jacket thereon, a core having a base insertable in the shell from the inner end, a head slidably mounted in the core in relation to the said base, a prong connected to the head and to the base, a fuse bar attached to said prongs, a contact in the base connected to the prong thereon, means to form an electrical connection from the prong on the head to the said jacket, and a spring in the core tensioned to thrust said head upwardly on the fusing of said fuse bar.

5. A fuse plug comprising in combination 120 a tubular shell having a conducting jacket with screw threads, a conducting resilient strip extending from the outside to the inside of said shell and engaging the conducting jacket, a core having a base with a recess and a contact screw with a conducting strip connected thereto, a head slideable in the base having a conducting plate, means forming a connection between said plate and the resilient strip, a fuse bar between the conducting 125 130

plate and the conducting strip on the base, and a spring bearing against the head to thrust same outwardly on fusing of the bar.

6. A fuse plug having a cylindrical shell with a conducting jacket thereon, said shell having a slot with a resilient conducting strip fitting therein, said strip having an electrical connection with the jacket, a core insertable in the shell and having a base with a contact 10 ing and a conducting strip on its end, a prong on the conducting strip, a head slideable in the core having a conducting plate thereon, a prong on said plate, a fuse bar fitted on said prongs on the plate and the conducting 15 strip, the conducting plate forming an elec-

tric connection with the resilient strip, and a spring in the core bearing against the base and the said head to force the said head outwardly on the fusing of the bar.

7. A fuse plug, as claimed in claim 6, the 20 base having lateral slots, the said conducting plate extending through said slots, there being a recess in the base, and the said spring being housed in said recess.

8. A fuse plug, as claimed in claim 6, the 25 resilient strip having a slot, and the prong on the conducting plate fitting in said slot.

In testimony whereof I have signed my name to this specification.

J. P. GILLIAM.
